(57) **CLAIM**

The ornamental design for a chicken feeder as shown and described.

DESCRIPTION

FIG. 1 is a front, left, top perspective view of a chicken feeder, showing my design in a first configuration;

FIG. 2 is a rear, right, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a rear, left, bottom perspective view of the chicken feeder in a second configuration;

FIG. 10 is a front, left, bottom perspective view of the chicken feeder in an exploded state for clarity of disclosure; and,

FIG. 11 is an enlarged view of detail 11, identified in FIG. 2.

The broken lines depict portions of the chicken feeder that form no part of the claimed design. The dot-dash broken lines in FIGS. 2 and 11 depict the boundaries of the enlargements that form no part of the claimed design.

1 Claim, 11 Drawing Sheets
